United States Patent Office.

D. A. GILBERT, OF MORRISTOWN, VERMONT.

Letters Patent No. 78,955, dated June 16, 1868.

IMPROVED BUTTER-TUB.

The Schedule referred to in these Letters Patent and making part of the same.

TO ALL WHOM IT MAY CONCERN:

Be it known that I, D. A. GILBERT, of Morristown, in the county of Lamoille, and in the State of Vermont, have invented certain new and useful Improvements in Butter-Tubs; and do hereby declare that the following is a full, clear, and exact description thereof, reference being had to the accompanying drawings, and to the letters of reference marked thereon.

In the annexed drawings, making part of this specification, A represents a butter-tub of any approved construction, and B represents its lid or cover.

C C represent three or more metallic hooks, which are secured to the tub upon its outside, and near its upper edge, the upper end of the hook extending above said edge. The cover B has three or more slots or openings, D D, cut in its rim, and on one side of each of these slots the wood of the rim is bevelled off, or an inclined surface is formed, as seen, from α to α . As the rim of the cover projects beyond the edges of the tub, it is necessary that the slots D D should be cut in it, in order to allow it to pass over the upper ends of the hooks C C.

When the cover has been placed upon the tub, and partially rotated, the inclined or bevelled portion of the rim, from α to α , catches under the upper lip of the hooks, and secures it firmly upon the tub.

By turning the cover sufficiently, the inclined surfaces upon its rim will tighten it upon the tub, so as to entirely exclude air. Any suitable packing may be used with it.

Having thus fully described my invention, what I claim as new, and desire to secure by Letters Patent, is—
The hooks C C upon the tub, when used in combination with the cover, provided with slots D D and the inclined surfaces, from α to α , as and for the purpose set forth.

In testimony that I claim the foregoing, I have hereunto set my hand, this 25th day of May, 1868.

D. A. GILBERT.
